UNITED STATES PATENT OFFICE.

JOSEPH P. BEM, OF BERKELEY, CALIFORNIA.

WHEELBARROW.

1,146,046.

Specification of Letters Patent. Patented July 13, 1915.

Application filed November 25, 1914. Serial No. 873,913.

To all whom it may concern:

Be it known that I, JOSEPH P. BEM, a citizen of the United States, residing at Berkeley, in the county of Alameda and State 5 of California, have invented new and useful Improvements in Wheelbarrows, of which the following is a specification.

The present invention relates to improvements in wheel-barrows, the object of the invention being to provide a wheel-barrow which will be especially convenient for working in confined spaces.

In the accompanying drawing, the figure is a perspective view of my improved wheel-barrow.

Referring to the drawing, 1 indicates the body of the wheel-barrow, to the under side of which is secured a V-shaped bar 2, between the members of which, near its bend, 20 extends a shaft 3 supported on a wheel 4. To said members beneath the body of the wheel-barrow are secured angular bars 5 forming legs for the wheel-barrow. Said members extend beyond the rear end of the 25 wheel-barrow, and on the extended portion 6 of each member a bracket or casting 7 is secured by a rivet 8 through said portion 6 and a rivet 9 through the rear end of the wheel-barrow. The upper portions of said 30 brackets are formed with bearings 10, open at the inner side, in which are contained the front portions of handles 11, the front ends of said handles being pivoted in said bearings by pivot pins 12 through said handles. 35 The handles can swing out from said bearings through their open sides upon said pivot pins and into a position extending across the rear end of the wheel-barrow and inclined slightly downward, as shown in 40 dotted lines. To secure the handles in their operative position in which they can be used for wheeling the wheel-barrow, there are provided tapered pins 13, to the heads of which are connected chains 14, which are 45 also connected to the wheel-barrow, said tapered pins passing through upper and lower holes 15, 16 in said brackets.

In use the empty wheel-barrow is wheeled to a position close to the face of the mine or 50 other excavation, the pins 13 are then removed from the holes 15, 16, and the handles drop into their transverse position or can easily be moved into said position by the application of a slight amount of force. 55 When the handles are in this position, ex-

tending transversely across the wheel-barrow, they offer no obstruction to the shoveling into the wheel-barrow of ore or dirt from a pile on the ground which has been picked down from the face of the mine. 60 Sometimes it is sufficient to permit one of said handles to extend transversely of the wheel-barrow. In working in trenches or in excavations for concrete work, the present construction also enables the operator to 65 place the wheel-barrow close to the work. The construction is also advantageous for carrying the wheel-barrow in an elevator car or down a shaft or for storing the same. It will be observed that there is no strain 70 upon the hinge pin, all the strain being taken up by the supporting bearing.

I claim:

1. In a wheel barrow, the combination of a body, brackets rigid therewith and extending therefrom and formed with bearings for the handles, and pivot pins through the front ends of said bearings and handles, the bearings being open on their inner sides to permit the handles to swing out of and 80 into the bearings.

2. In a wheel barrow, the combination of a body, brackets rigid therewith and extending therefrom and formed with bearings for the handles, and pivot pins through 85 the front ends of said bearings and handles and inclined slightly inward upwardly, the bearings being open on their inner sides to permit the handles to swing out of and into the bearings.

3. In a wheel barrow, the combination of a body, brackets rigid therewith and extending therefrom and formed with bearings for the handles, pivot pins through the front ends of said bearings and handles, taper 95 pins securing said handles in their rearwardly extending positions in said bearings, the bearings being open on their inner sides to permit the handles to swing out of and into the bearings.

4. In a wheel-barrow, the combination of a body, bars upon which the same is supported and extending past its rear end, brackets secured to said extended portions of the bars and also to the body and formed 105 with bearings, handles in said bearings pivoted upon approximately vertical pivots, said bearings permitting the handles to swing into a position transverse of the wheel-barrow.

100

110

5. In a wheel-barrow, the combination of a body, bars upon which the same is supported and extending past its rear end, brackets secured to said extended portions of the bars and also to the body and formed with bearings, handles in said bearings pivoted upon approximately vertical pivots, said bearings permitting the handles to swing into a position transverse of the
- 10 wheel-barrow and tapered pins securing said

handles in their rearwardly extending positions in said bearings.

In testimony whereof I have hereunto set my hand in the presence of two subscribing witnesses,

JOSEPH P. BEM.
